ROLLER STOCK PUSHER FOR SCREW MACHINES

Filed July 1, 1931

INVENTOR:
Edward R. Dingell.
by *Grover Red Hill,*
Attorney.

UNITED STATES PATENT OFFICE

EDWARD R. DINGELL, OF DETROIT, MICHIGAN

ROLLER STOCK PUSHER FOR SCREW MACHINES

Application filed July 1, 1931. Serial No. 548,099.

My invention relates to stock pushers for automatic or hand screw machines and provides a device of this character embodying a shell having a plurality of equally spaced rollers adapted to rotate within the shell and to contact the bar stock sufficiently to convey the end of the same to the operating tools.

The outstanding advantage of my invention is that it protects the bar stock from being scratched, marked or otherwise injured as result of the stock pushers of the present time, which are usually made of a split tubular construction, and the sliding upon the bar causes the inner surface thereof to wear to such extent that it must be replaced by an entire new tool, whereas in my invention as the hardened rollers become worn the complete tool may be placed in order as a new one by merely replacing the worn rollers with new ones, which would be considerably much less expensive than replacing the entire tool.

The invention possesses further advantages, all of which will be clearly revealed during the course of the following detailed description, illustrated throughout the accompanying drawings, and more fully pointed out in the appended claims.

With direct reference to the drawings: Figure 1 is a longitudinal section of the complete invention in the act of operation, and through the center thereof.

Figure 2 is a side elevation, and Figure 3 is an end elevation.

Figure 4 is a section taken substantially upon line 4—4 of Figure 2, and Figure 5 is a section taken upon line 5—5 of Figure 2.

Figure 6 is a fragmentary view of one of the rollers and locking elements.

The invention comprises shell 1 which is provided with externally threaded shank 2 adapted to engage the internally threaded supporting tube A. Shell 1 has enlarged wall as indicated at 3 to provide metal of ample thickness for pockets therein to accommodate a plurality of rollers 4, and the said rollers to contact bar stock B as clearly indicated in Figures 1 and 5.

A novel feature is arranged to prevent rollers 4 from working out of shell 1, and for

this purpose adjacent the front end of each of the said rollers a threaded hole is provided through portion 3 of the said shell, and the said hole adapted to receive headless screw 5, and the slots of the said screws are then circumferentially aligned and are effectively locked in this position by split ring 6, which is of a spring nature; this is clearly seen in Figure 4. It is also noted that elongated slots 7 are provided in the shell 1, and are diametrically opposed, as indicated in Figures 2, 3 and 5. The purpose of slots 7 is to provide adequate spring in shell 1 to permit the same to be closed in as rollers 4 become worn. Hole 8 in shell 1 is for the application of a suitable wrench for connecting the device to tube A, or likewise disengaging these elements.

With the aid of the accompanying drawings I have hereinabove disclosed one precise embodiment of my invention. The same is nevertheless susceptible to certain minor changes in the details of construction thereof, however in the event of the necessity of any changes of this character during any probable further development of the invention for the market, a departure from the general principle as described and later claimed would be consistently avoided.

Having thus described my invention what I claim as new is:

1. In a device of the character described, a principal tubular shell for the same, the said shell to telescopically engage the bar stock being fed to the screw machine, means within one end of the said shell for conveying the said bar stock to the operating tools therefor, and this means comprising a plurality of spaced apart rollers in circumferential formation within the said shell, and the said rollers to contact and feed the said bar stock as aforesaid, also means for retaining the said rollers in their respective operating position comprising a plurality of concentrically arranged screws within the said shell, and one of the said screws adjacent the front end of each of the said rollers, means for locking all of the said screws relatively to the backing out thereof, and this means comprising a split ring, the said ring adapted to engage

all of the slots of the said screws when they are in circumferential alignment.

2. In a roller stock conveyor for screw machines, an elongated shell for the same, one end of the said shell having an externally threaded shank to engage an internally threaded tubular supporting member, the opposite end of the said shell having a wall of an increased thickness, a plurality of spaced apart elongated pockets in circumferential formation, within the said enlargement, a roller adapted to fill and rotate within each of the said pockets, and all of the said rollers to contact and convey the said bar stock to the operating tools of the screw machine, a plurality of spaced apart screws in circumferential formation within the said shell, and one of the said screws adjacent the outer end of each of the aforesaid rollers to prevent the said rollers from working out of their original position, a split ring for the device, the slots of all of the aforesaid screws being placed in circumferential alignment and the said ring adapted to engage all of the said slots for the purpose of locking the said screws in their respective positions; a plurality of elongated slots within the aforesaid shell and extending partly the length thereof from the enlarged end of the same, for the purpose of effecting a spring in the said shell in order that the same may be closed in for adjusting the aforesaid rollers with relation to the aforesaid bar stock, also an aperture through the thinner wall of the said shell for the application of a wrench.

In testimony whereof I hereunto affix my signature.

EDWARD R. DINGELL.
